Charles W. Mitchell and Samuel S. Aidlin,
New York, N. Y.

Application December 27, 1952, Serial No. 22,894

Term of patent 14 years

(Cl. D26—13)

To all whom it may concern:

Be it known that we, Charles W. Mitchell and Samuel S. Aidlin, both citizens of the United States of America and both residents of the city of New York, county of Kings and State of New York, have invented a new, original, and ornamental Design for a Thermostatic Fire Alarm Switch, of which the following is a specification, reference being had to the accompanying drawing, forming a part hereof, wherein

Fig. 1 is a plan view of the outer face of a thermostatic fire alarm switch showing our new design;

Fig. 2 is a plan view of the reverse side thereof;

Fig. 3 is a side elevational view of the same; and

Fig. 4 is a perspective view looking upwardly at the same.

The dominant features of our design reside in those portions shown in full lines.

We claim:

The ornamental design for a thermostatic fire alarm switch, substantially as shown and described.

CHARLES W. MITCHELL.
SAMUEL S. AIDLIN.
